UNITED STATES PATENT OFFICE.

WILLIAM M. SKELTON, OF GREENCASTLE, INDIANA, ASSIGNOR OF TWO-THIRDS TO ELLIS B. DOOLEY AND FRANCIS SKELTON, BOTH OF SAME PLACE.

SHAM PILLOW.

SPECIFICATION forming part of Letters Patent No. 387,603, dated August 7, 1888.

Application filed February 13, 1888. Serial No. 263,885. (No model.)

To all whom it may concern:

Be it known that I, WILLIAM M. SKELTON, a citizen of the United States, and a resident of Greencastle, in the county of Putnam and State 5 of Indiana, have invented certain new and useful Improvements in Sham Pillows; and I do declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 Figure 1 of the drawings is a representation of this invention and is a top view. Fig. 2 is a vertical section. Fig. 3 is a top view.

The invention relates to improvements in pillows designed more particularly as a dress 20 or sham pillow for beds; and it consists in the construction and novel combination of parts as hereinafter set forth.

Referring to the drawings, A designates 25 light wooden parallel slats, and B represents similar parallel slats at right angles to the slats

A. Pivot-pins *a* pass through the slats A and B at their several points of junction.

The two sides of the device are similarly 30 constructed, and are connected by the outwardly-curved spring-plates C.

The springs C at their ends overlap two bars

on each side, as shown, and the pivots *a* serve to hold the springs in place. Corner outwardly-curved springs D are pivoted to the corners of the opposite sides, and are designed 35 to fill out the corners of the casing that may be drawn over the frame.

The pivotal connections of the parts allow the frame to be turned in a diamond form, as shown in Fig. 3 of the drawings.

It will be observed that the springs C are at all times parallel on the respective edges.

Having described my invention, what I claim is—

1. In a sham pillow, the combination of the 45 rectangular frames placed one above the other and composed of the slats A, B, pivotally connected to each other and connected by the outwardly-curved pivoted springs C, and the corner-springs, substantially as specified.

2. In a sham pillow, the combination of the 50 rectangular frames composed of slats pivotally connected together and at right angles to each other, and the outwardly-curved springs joining said frames together, substantially as 55 specified.

In testimony whereof I affix my signature in presence of two witnesses.

WILLIAM M. SKELTON.

Witnesses:

W. H. RAGAN,
MARSHAL B. GIRTON.
